SAVINGS BANK

Nathan B. Lerner, Chicago, Ill., assignor to Harold B. Spector and Raymond B. Spector, doing business as Superior Toy & Mfg. Co., a co-partnership

Filed Jan. 9, 1963, Ser. No. 250,427

8 Claims. (Cl. 232--5)

This invention relates to a bank, and more particularly to a savings bank especially suitable for accommodating coins of various denominations and designed to stimulate the savings habit among children as well as adults.

Numerous small savings banks have been on the market for many years, but in view of their structural design they are beset with one or more shortcomings, such as (a) they are of delicate construction and readily susceptible to damage; (b) they are unable to accommodate coins of varying denominations; (c) they are difficult and awkward to open and close; and (d) they are of expensive, bulky, and unattractive construction. In addition these prior constructions did not readily indicate to the saver the amount of money disposed within the bank and thus the saver was not stimulated to watch his or her savings grow.

Accordingly, it is one of the objects of this invention to provide a savings bank which is not beset with the aforesaid shortcomings, and yet combines economy of manufacture with quality and attractiveness.

It is a further object of this invention to provide a savings bank which contains a plurality of vertical compartments suitable for accommodating several size coins in such a way that coins may not be accidentally removed from the bank when the latter is subjected to abusive handling.

It is a still further object of this invention to provide an effective, but inexpensive, key actuated locking mechanism which is embodied in the support for the housing having coin-accommodating compartments.

It is a still further object of this invention to provide a savings bank with the housing provided with the coin-accommodating compartments fabricated from a transparent material and mounted for rotation about a vertical axis.

It is a still further object of this invention to provide a savings bank which is possessed of stability regardless of the quantity of coins accommodated thereby.

Further and additional objects will appear from the description, accompanying drawing and appended claims.

In carrying out this invention in one form, a hollow, octagonally-shaped outer housing open at both ends is provided which is preferably of a transparent material. Disposed within the housing is a divider which cooperates with the interior surface of the housing to form a plurality of symmetrically arranged coin-accommodating compartments. The compartments are of various configurations so that each is adapted to accommodate a coin of a particular, yet different, denomination (i.e. penny, nickel, dime, quarter, etc.). Adjacent the upper end of each compartment and in communication therewith is a slot which is formed in the exterior surface of the housing. Each slot is sized so as to permit coins of a particular denomination to readily pass therethrough into the adjacent pocket. Means cooperates with each slot so as to permit coins to pass therethrough in only one direction. A cover overlies the upper ends of the housing and divider and cooperates therewith to form a unitary structure or assembly. The assembly is removably mounted on a pedestal which in turn is mounted for rotary movement on a base. The base includes a locking means which, when in one position of adjustment is adapted to fixedly retain the assembly on the pedestal and, when in a second position of adjustment is adapted to permit the assembly

2

to become disengaged from the pedestal whereupon the lower end of each compartment is exposed to permit the coins accommodated in the compartments to be removed therefrom.

5 For a more complete understanding of this invention, reference should now be made to drawings herein.

FIG. 1 is a perspective view of the improved savings bank showing a plurality of coins accommodated therein.

10 FIG. 2 is a bottom view of the bank of FIG. 1 whereby the locking mechanism is exposed.

FIG. 3 is an enlarged sectional view taken along line 3-3 of FIGURE 2.

FIG. 4 is an enlarged perspective view of a key for actuating the locking mechanism.

15 FIG. 5 is an enlarged sectional view taken along line 5-5 of FIGURE 1.

FIG. 6 is an enlarged fragmentary view of one of the compartment slots and showing a portion of a coin in dotted lines about to pass therethrough.

20 FIG. 7 is similar to FIG. 6 but showing the coin passing through the slot.

FIGS. 8 and 9 are enlarged fragmentary plan views, partially in section, of the locking mechanism shown, respectively, in unlocked and locked positions.

25 FIG. 10 is an enlarged fragmentary plan view of the printed insert which serves to restrict passage of coins in only one direction through the compartment slots.

FIG. 11 is an enlarged fragmentary elevational view of the upper slotted ends of the compartments and showing the insert of FIG. 10 in assembled relation with the housing and divider.

Referring now to the drawings and more particularly to FIGS. 1 and 3, an improved bank 20 suitable for saving coins of different denominations is shown. The bank

35 comprises an open-ended outer housing or shell 21 preferably formed of a transparent plastic material. The housing 21 in the illustrated embodiment has an octagonal configuration in cross-section. Disposed within the housing is an elongated divider or spider 22 which cooperates with the faceted interior surface of the housing to form a plurality of symmetrically arranged compartments or cavities 23, 24, 25, 26, 27, 28, 30 and 31. Each compartment extends the full length (height) of the housing 21 and is sized to accommodate a coin of a selected

40 denomination (i.e. penny, nickel, dime, quarter, half dollar, or dollar). Two or more of the compartments may be of the same size so as to accommodate coins of the same denomination (i.e. compartments 24 and 31, FIG. 5). The compartments are separated from one

45 another by radially extending finger-like partitions 22a. The distal end of each partition terminates adjacent the interior surface of the housing. One of the partitions 22a, see FIG. 3, has a lug 22'a which projects outwardly a slight amount and contacts the interior surface of housing 21. The purpose of this lug will be described more fully hereinafter. The inner ends of the partitions 22a

50 are interconnected so as to form a hollow hub section 22b, see FIG. 5. The upper end of the housing 21 and divider are covered over by a cover piece 32, which is preferably formed of a chrome-plated metal so as to provide a highly decorative appearance. A peripheral flange 32a

55 is provided on cover piece 32 which overlies the exposed upper surface of the housing 21. The center of cover piece 32 is provided with an opening 32b through which projects outwardly a knob 33. The function of the knob will be described more fully hereinafter.

Depending from knob 33 is an elongated rode 34, which passes through the hollow interior of hub 22b. The lower end of the hub is closed except for a relatively small opening 22c through which the rod 34 passes. The lower end of rod 34 terminates with a locking mechanism 35,

60 to be described more fully hereinafter, and is provided

65

70

Depending from knob 33 is an elongated rode 34, which passes through the hollow interior of hub 22b. The lower end of the hub is closed except for a relatively small opening 22c through which the rod 34 passes. The lower end of rod 34 terminates with a locking mechanism 35, to be described more fully hereinafter, and is provided

with an enlarged collar 34a. Spaced longitudinally above collar 34a is a first protuberance 34b which is impassable relative to hub opening 22c and a second protuberance 34c, see FIG. 3, which is disposed within a peripheral slot 22c formed in one side of opening 22c. Protuberance 34c and slot 22c cooperate to permit the housing and divider to be rotated as a unit about the rod as an axis.

It will be noted in FIG. 3 that the upper end 34d of rod 34 is press fit into knob 33. If desired, however, once the divider 22, housing 21, cover 32, and a transparent insert 36, see FIG. 10, have been brought into assembled relation and the rod 34 passed through hub opening 22c until the rod protuberance 34b contacts the underside of the lower end of hub, the knob 33 and upper end 34d or the rod may be permanently assembled.

The transparent insert 36 is preferably formed of a thin sheet of relatively stiff, yet bendable, plastic material. The sheet is adapted to be bent so as to conform to the interior surface configuration of housing 21. The insert 36, subsequent to being bent, is positioned intermediate the outer periphery of divider 22 and the interior surface of housing 21 and is held therebetween by friction. The upper edge of insert 36 is provided with a plurality of spaced projections 36a. Intermediate one pair of projections 36a is a slotted projection 37, see FIG. 10, the slot 37a of which is adapted to accommodate the divider lug 22a when the insert 36 is in assembled relation with the divider and housing. The slot and lug arrangement is provided so as to insure that the insert 36 will always assume a predetermined position whereby the projections 36a will be centrally aligned with respect to the compartments.

Vertically aligned with each projection 36a are calibrated indicia 38 which are preferably printed on one surface of insert 36, see FIG. 10. When the insert 36 is assembled with the divider and housing, the indicia 38 will line up with predetermined compartments 23-28, 30, 31 and indicate the amount of coins which are accommodated in stacked relation within a given compartment.

As seen more clearly in FIGS. 1, 6, and 7, the housing 21 is provided, adjacent the upper end thereof with a plurality of symmetrically arranged slots 21a; each slot communicates with a given compartment formed by divider 22 and the interior surface of housing 21. The slots 21a permit coins 40, see FIG. 7, to readily pass therethrough into the corresponding compartment. It will be noted in FIG. 6, that an insert projection 36a extends above the lower portion of the slot 21a and thus, prevents a coin, once accommodated within the compartment, from accidentally falling out of the compartment through the slot when the bank is vigorously shaken in an inverted position. The function of each insert projection 36a is akin to that of a one-way valve. The resiliency of the material utilized in forming the insert is such that the projections may be readily bent to a substantially horizontal position as the coin passes through the slot 21a, see FIG. 7.

The lower ends of the coin compartments 23-28, 30, and 31 are closed by a pedestal piece or saucer-like member 41. The peripheral configuration of piece 41 is the same as cover 32 and is provided with an upstanding flange 41a which overlies the lower exposed surface of housing 21. The center of piece 41 is provided with an oversized opening 41b through which the lower collared end 34a of rod 34 extends. When the rod end collar 34a is removed from locking mechanism 35, piece 41 may be removed from the bottom of the housing, whereupon the accommodated coins may be readily withdrawn from the various compartments while the housing 21, divider 22, cover piece 32, rod 34, knob 33, and insert 36 remain in assembled relation.

The locking mechanism 35, previously mentioned, is mounted within a hollow base 42. The upper surface 42a of the base is provided with a raised spindle 42b

having a center opening 42c through which the lower end of the rod 34 extends.

Depending from the outer periphery of surface 42a is a continuous flange 42d which is adapted to engage the supporting surface upon which the bank is placed. A second shorter depending annular flange 42e is formed on the underside of surface 42a. It will be noted in FIGS. 2 and 3 that the center of curvature of flange 42e is eccentrically disposed with respect to the axis of rod 34. The underside of surface 42a delimited by flange 42e is recessed slightly so as to form an annular shoulder 42f. The symmetry of this shoulder is interrupted at one location by a stop lug 42g. Adjacent the lower edge of second flange 42e is formed a second inner annular shoulder 42h.

Disposed within the area delimited by second flange 42e and slidably engaging shoulder 42f is a flat cam piece 43 formed preferably of metallic material, see FIGS. 8 and 9. The outer periphery of cam piece 43 is of a uniform annular configuration, except for an arcuate segment 43a which is recessed to accommodate stop lug 42g. The arc of segment 43a in the illustrated embodiment is approximately ninety (90°) degrees, thus permitting the cam piece 43 to be rotated through such an arc about the center 43b of the piece as an axis.

Arranged substantially diametrically opposite peripherial segment 43a and spaced inwardly of the cam periphery is an arcuate slot 43c. The extent of slot 43c is approximately 90° and one end 43d thereof is enlarged so that the rod end collar 34a may pass therethrough. The radial dimension of the balance of the slot is such that rod 34 is free to slide therein, but end collar 34a cannot pass therethrough. Thus, when cam piece 43 is in the relative position shown in FIG. 8, the rod end collar 34a is free to be withdrawn from the locking mechanism 35 and the pedestal piece 41 removed from the housing 21. In FIG. 9, the cam piece 43 has been rotated in a clockwise direction through an arc of approximately 90° whereby the locking mechanism 35 and the rod 34 are in interlocking relation.

To effect retention of the cam piece 43 in its locking position, see FIG. 9, a spring loaded detent 44 is provided in the underside of surface 42a. The detent is adapted to releasably engage an opening 43e formed in cam piece 43.

Rotation of cam piece 43 is effected by a key 45, see FIG. 4, which is provided with a pair of spaced tongues 45a. These tongues are adapted to engage a pair of spaced apertures 43f formed in cam piece 43 adjacent the center 43b thereof. The tongues 45a are formed on the distal end of an elongated neck section 45b, the latter constituting a part of key 45.

Cam piece 43 is held in place against shoulder 42f by a disc shape member 46 adhesively affixed to the interior surface of flange 42e. Member 46 is provided with an upstanding annular flange 46a which is spaced inwardly a slight amount from the outer periphery thereof so as to form a ledge 46b which contacts shoulder 42h, see FIG. 3. The height of flange 46a is such that it engages the underside of cam piece 43 but not with such force as to interfere with the rotational movement of the piece by key 45. Furthermore the area delimited by flange 46a forms a cavity 47 which is adapted to accommodate end collar 34a when it is in assembled relation with the locking mechanism 35.

Disc member 46 is also provided with a central opening 46c through which the neck section 45b and tongues 45a of the key are adapted to pass so that the tongues will engage the apertures 43f.

The base 42 may be formed of sturdy molded plastic material or of metal, if desired. While the housing 21 is illustrated as having an octagonal configuration, it is to be understood of course that the invention is not limited to this particular shape but may assume various other shapes depending upon individual tastes. Likewise the

exterior shape of base 42 may be different from that shown and will be such as to complement the shape of the housing 21.

Thus it will be seen that a simple, attractive, inexpensive, and sturdy savings bank has been provided. Furthermore because of its unique construction, the device acts to stimulate the savings habit among children as well as adults. The bank by reason of its construction is readily capable of accommodating coins of varying denominations.

While a particular embodiment of this invention is shown herein, it will be understood, of course, that the invention is not to be limited thereto, since many modifications may be made, and it is, therefore, contemplated by the appended claims to cover any such modifications as fall within the true spirit and scope of this invention.

I claim:

1. A savings bank for coins and the like comprising a base, a rotatably adjustable locking mechanism mounted on said base, and a compartmented coin-accommodating unit mounted upright on said base; said unit including an elongated depending element accommodated by said locking mechanism and in interlocking engagement therewith, when said mechanism is in one position of adjustment, and disengageable from said mechanism, when the latter is in a second position of adjustment whereby said unit is detachable from said base, the longitudinal axis of said depending element being offset with respect to the rotary axis of said locking mechanism, and a plurality of compartments arranged in upright substantially parallel spaced relation, a corresponding one end of each compartment being closed by a removable member, said member being removable from said compartment one end to expose said compartment interior, only when said depending element is disengaged from said locking mechanism and said base, each compartment being provided with an entrance through which a coin is capable of passing.

2. A savings bank for coins and the like comprising a base, an adjustable locking mechanism mounted on said base, and a compartmented coin-accommodating unit mounted on said base for rotation about an upright axis; said unit including an elongated depending element coaxial with said rotary axis, said element being accommodated by said mechanism and in interlocking engagement therewith, when said mechanism is adjusted independently of said element to one position of adjustment, and disengageable from said mechanism, when the latter is adjusted independently of said element to a second position of adjustment whereby said unit is removable from said base, a plurality of coin-accommodating upright compartments arranged in spaced substantially parallel relation and symmetrically about the longitudinal axis of said depending element, a corresponding one end of each compartment being closed by a removable member, the latter being removable from said compartment one end to expose said compartment interior, only when said unit is removed from said base, each compartment having an exposed outer wall provided with means for observing the interior of such compartment, each com-

partment being provided with an entrance through which a coin is capable of passing in only one direction.

3. The bank recited in claim 2 wherein the exposed outer wall of each compartment is transparent throughout substantially the entire height of said compartment.

4. The bank as recited in claim 3 wherein each exposed outer compartment wall is provided with calibrated indicia extending substantially the full height of said wall.

5. The bank recited in claim 1 wherein the unit comprises a hollow member open at its lower end and having the interior thereof provided with a plurality of coin-accommodating compartments, each compartment having an exposed outer wall through which the interior of the compartment can be observed, an entrance for each compartment formed in the outer wall thereof and adjacent the upper end of said housing, and coin-contacting resilient means disposed within each entrance for permitting movement of a coin through such entrance only in a direction toward the interior of the compartment.

6. The bank recited in claim 1 wherein said unit is mounted for rotation relative to said base about said elongated depending element as an axis.

7. The bank recited in claim 1 wherein said unit includes a central section provided with a plurality of upright symmetrically arranged coin-accommodating compartments, each compartment having an exposed transparent outer wall and an entrance through which a coin is capable of passing in only one direction, a top section overlying and closing off the upper ends of all of said compartments, a removable bottom section subtending said central section and closing off the lower ends of said compartment; said bottom section being removable from said central section, only when said unit is detached from said base, whereby the interior of each compartment is exposed to permit removal therefrom of coins accommodated within said compartments.

8. The bank recited in claim 1 wherein said locking mechanism includes a hollow body portion mounted beneath the upper surface of said base, said base upper surface being provided with an opening communicating with the interior of said body portion and through which the unit depending element extends; an apertured cam piece mounted within said body portion for limited rotation about a vertical axis offset from, but parallel to, the longitudinal axis of said depending element, an aperture of said cam piece being of arcuate configuration and in continuous registration with said base surface opening and slidably accommodating said depending element, one terminal of said arcuate aperture being enlarged whereby said depending element is vertically adjustable only when said element is disposed at said one terminus; and manually adjustable means engageable with said cam piece to effect limited rotation thereof.
